UNITED STATES PATENT OFFICE

EDGAR H. BURROUGHS, OF SCARSDALE, NEW YORK, ASSIGNOR TO AMBURSEN CONSTRUCTION COMPANY, INC., OF NEW YORK, N. Y., A CORPORATION OF NEW YORK

DAM

Application filed April 30, 1930. Serial No. 448,504.

This invention relates to a novel and improved form of dam and the novel features will be best understood from the following description and the annexed drawing, in

5 which

Fig. 1 is a vertical sectional view through one form of a dam constructed according to this invention, this section being taken on a plane extending up and down stream.

10 Fig. 2 is a section on the line 2—2 of Fig. 1.

Referring now to the drawing, in which I have shown a selected embodiment of the invention, the up-stream water-bearing deck is indicated as a plurality of arches or domes 15 7 and 8. The term "deck" as herein used is intended to cover not only the specific form of water-bearing member illustrated herein but also any other structure adapted to form a water-bearing surface in contact with the 20 water above the dam. For example, the deck may take the form of the well-known flat slab construction.

In order to distribute the stresses from the deck through the superstructure to the 25 foundation in a more efficient manner than hitherto, I support the deck upon walls extending lengthwise of the dam, the walls here being shown as two in number and indicated at 9 and 10, the wall 10 being shown 30 as forming a continuous down-stream face for the dam.

Preferably these walls 9 and 10 are arranged approximately normal to the deck, although it is within the scope of this invention to have them vertical, or at some 35 other angle to the deck than the one indicated. Preferably the tops of the walls are flared as indicated at 11 and 12, respectively, and are also flared at their bottom portions 40 as indicated at 13 and 14, respectively. When the deck is formed in spherical domes as indicated, the flared portions 11 and 12 are joined to the domes by substantially continuous curves as indicated, and the walls 9 45 and 10 are disposed in position to support the domes at their springing lines.

Referring now to Fig. 2, it will be seen that I have shown a plurality of walls 15 extending up and down stream and disposed 50 transversely of the walls 9 and 10 and at the

springing lines of the domes 7 and 8. These walls 15 are integrally joined to the deck by flared portions 16 and to the walls 9 and 10 by similar flared portions 17.

By the above construction a number of 55 advantages are obtained. Among these may be mentioned the drawing down stream of the center of gravity of any horizontal section thereby moving the center of gravity nearer to the point of application of the 60 resultant of loads acting on that section, and thereby giving a more uniform distribution of stresses throughout the section. The arrangement of flared walls further makes a construction in which the span of the 65 water-bearing deck is decreased between supports, thereby making possible the greater spacing of supports for the same thickness of deck, with the resultant economy in material. Another advantage resides in the 70 cellular arrangement which results from this construction, this cellular construction adding greater strength to the dam as a whole.

If desired, the down-stream wall 10 may be provided with joints, one of which is 75 shown at 18, or under certain conditions it may be interrupted between walls 15 to form a gap in the wall, thus saving material in case the strength of a continuous wall is not needed in the particular dam under consideration.

I claim:

1. A dam with an up- and down-stream section comprising an arch having abutments in foundation material with the up- 85 stream abutment terminating substantially normal to the surface of said material, a second arch having one abutment on said first-named arch adjacent the crown thereof, with said arches presenting up-stream 90 surfaces forming a water-bearing deck.

2. A dam with an up- and down-stream section comprising an arch having abutments in foundation material with the up- 95 stream abutment terminating substantially normal to the surface of said material, a second arch having one abutment on said first-named arch adjacent the crown thereof and the other abutment on foundation material, with said arches presenting up- 100

stream surfaces forming a water-bearing deck.

3. A dam with an up- and down-stream section comprising an arch having abutments in foundation material with the up-stream abutment terminating substantially normal to the surface of said material, and a second arch having one abutment on said first-named arch adjacent the crown thereof, with said arches presenting up-stream surfaces forming a water-bearing deck and walls extending up- and down-stream beneath said deck and spaced apart lengthwise of the dam.

15 4. A dam with an up- and down-stream section comprising an arch having abutments in foundation material with the up-stream abutment terminating substantially normal to the surface of said material, and 20 a second arch having one abutment on said first-named arch adjacent the crown thereof, with said arches presenting up-stream surfaces forming a water-bearing deck and walls extending up- and down-stream beneath said deck and spaced apart lengthwise 25 of the dam, said deck being arched between said walls.
